SUBMERSIBLE SUMP PUMP CONTROL

Edward J. Schaefer, Fort Wayne, Ind.

Application February 17, 1951, Serial No. 211,544

9 Claims. (Cl. 103—26)

1

This invention relates generally to sump pumps and more particularly to a novel control means for a sump pump of the submersible type.

In my copending application S. N. 177,674, filed August 4, 1950, I have described and claimed a sump pump arrangement wherein the electric motor for the pump unit is of the submersible type and is positioned immediately adjacent the pump unit. The motor is rendered submersible by means of a generally cylindrical shell or enclosure which includes a flexible diaphragm means adapted to actuate a control switch for the motor in response to changes of water level outside the enclosure. Preferably, the diaphragm means constitutes an end portion of the motor enclosure and, in addition, the diaphragm means is preferably arranged so that the entire motor enclosure functions as a float control.

With the sump pump arrangement comprising my earlier invention the pump is automatically turned on when the water in the sump reaches a predetermined maximum level sufficient to deflect the diaphragm means and actuate the control switch. The pump continues to operate until the water in the sump recedes to a minimum level such that the head of water in the sump is insufficient to deflect the diaphragm means whereupon the control switch returns to its normal off position. Thus, it will be seen that the device functions to maintain the water in the sump at a certain minimum level but in no case is the sump actually pumped to substantial emptiness.

The present invention relates to a control means adapted to be used in combination with a sump pump arrangement of the type disclosed in my earlier copending application for the purpose of insuring continued operation of the pump until the sump is substantially dry.

Accordingly, a primary object of my invention is to provide a novel sump pump arrangement adapted to empty a sump or the like to substantial dryness.

A further object of the invention is to provide novel control means for a sump pump which insures continued operation of the pump until it begins to draw air.

Another object of the invention is to provide a novel submersible sump pump arrangement having a motor enclosure including main control means for the motor and an auxiliary control device adapted to cooperate with the main control means for insuring operation of the pump until it ceases to discharge liquid.

Other objects and advantages of the invention will become evident from the subsequent detailed

2

description taken in conjunction with the accompanying drawing wherein:

Fig. 1 is a vertical sectional view of a sump pump arrangement comprising one specific embodiment of my invention; and

Fig. 2 is a view similar to Fig. 1 but showing a modified form of the invention.

Referring first to Fig. 1 of the drawing, wherein one specific embodiment of my invention is shown merely by way of illustration, the device comprises an electric motor 6 of a conventional type having a rotor shaft 7 depending therefrom. Disposed below the motor 6 and immediately adjacent thereto is a centrifugal pump unit 8 of a conventional type having an inlet 9 and an outlet 11 and arranged so that the pump casing supports the weight of the motor. The pump impeller, indicated at 12, is secured at the lower end of the shaft 7 and the latter is provided with a suitable rotating seal 13 to prevent entry of water to the motor through the shaft outlet.

Surrounding the motor 6 for rendering the latter submersible is an enclosure, indicated generally at 14, which comprises a cylindrical body portion 16 supported on the motor 6 by means of a pair of substantially identical upper and lower end portions designated generally by the reference numeral 17. The body portion 16 is preferably formed from relatively thin corrosion-resistant metal such as stainless steel.

Each of the end portions 17 of the enclosure 14 comprises a deflectable diaphragm means including a relatively thin annular element 18 which may be of metal. The outer marginal or peripheral edge of each of the elements 18 is turned inwardly toward the motor 6 to provide a flange or rim 19 which is rigidly secured and sealed, preferably by welding, to the inner periphery of the body portion 16 of the enclosure 14. The inner marginal or peripheral edge of each element 18 is turned outwardly away from the motor 6, as at 21, and is flexibly attached to the motor 6 by means of an annular connecting collar, indicated generally at 22. The collars 22 are preferably formed from a resilient material such as rubber or the like and are generally U-shaped in cross-section. Thus, each of the collars 22 is formed with relatively heavy concentric inner and outer ring portions 23 and 24, respectively, which are interconnected adjacent their outermost edges by a relatively thin integral connecting portion 26. The collars 22 are secured to the elements 18 by means of the outwardly turned edges 21 of the latter which are flared outwardly to a slight extent in order to

provide a snug engagement with the inner periphery of the collar portions 24. The inner portions 23 of the collars 22 fit snugly around the upper and lower hub portions of the motor 6, as indicated at 27 and 28, respectively.

Thus, the combination of the enclosure 14 with the upper and lower end portions or diaphragm means 17 forms a watertight casing which renders the motor 6 submersible and at the same time constitutes a float which is free for limited movement in a vertical direction upon flexing of the connecting portions 26 of the collars 22, as hereinafter described.

For automatically regulating the operation of the motor 6, a control switch 29 having a depressible spring-pressed operating member or button 31 is mounted adjacent the upper portion of the motor 6 with the operating button 31 facing the upper annular element 18 in operative relation therewith. The switch 29 is of a type in which only a relatively slight movement of the operating button 31, e. g. $\frac{1}{2}$ of an inch, is sufficient to cause the actuation of the switch between "on" and "off" positions. It will be understood that the enclosure 14, which is sealed to the upper and lower ends of the motor 6 by the end diaphragm means 17, will function as a float when the motor and pump unit are disposed at the bottom of a sump. Thus, as the water level in the sump rises, the enclosure 14 containing trapped air is lifted upwardly relative to the motor 6 by the buoyant effect of the water, the flexible connecting portions 26 of the collars 22 permitting this upward movement. Upon upward movement of the enclosure 14, the upper element 18 moves away from the operating button 31 permitting the latter to move outwardly whereby to complet the electrical circuit for the motor 6 and thereby start the pump 8 in operation. Similarly, as the water level in the sump recedes during operation of the pump 8, the weight of the enclosure 14 causes the latter to move downwardly whereupon the upper element engages the switch button 31 and depresses the latter to shut off the motor.

Means comprising a bridge member and guide screws (not shown in detail in the drawing) is provided at the upper end of the motor for guiding and limiting the vertical movement of the float enclosure 14 relative to the motor 6. Details of this structure are described fully in my copending application S. N. 177,674 and need not be repeated here. A dome-shaped cover 32 is detachably mounted over the upper end of the device with the depending skirt portion thereof fitting over and frictionally engaging the upper end of the body 16 of the enclosure 14, as at 33. A handle 34 is fastened to the cover 32 for raising and lowering the entire unit. Means (not shown) comprising suitable electric wires is also provided for conducting electric current to the switch 29 and the motor 6.

As the motor 6 heats up during operation, the temperature of the air trapped inside of the enclosure 14 may vary as much as 50° C. Under such circumstances it is desirable to compensate for varying air pressure in order to avoid the possibility that an increase in air pressure inside the enclosure might cause movement of the enclosure relative to the motor and thereby effect the operation of the device independently of any change of water level. However, the provision of substantially identical diaphragm means 17, i. e. diaphragm means having substantially the same exposed areas, at the top and bottom of the

cylindrical portion 16 of the enclosure 14 balances out the effect of varying air pressure within the enclosure and leaves the upward and downward movement of the enclosure 14 dependent solely upon external pressure. In other words, even if the pressure of the air surrounding the motor 6 and within the enclosure 14 should increase, the net force tending to move the enclosure 14 relative to the motor 6 will be zero because the force acting against the upper diaphragm means 17 tending to move the enclosure 14 upwardly will be counteracted by a substantially identical force acting against the lower diaphragm means 17 tending to move the enclosure 14 downwardly. The cover 32 is provided with suitable means (not shown) for permitting drainage of water from the space between the cover 32 and the upper diaphragm means 17 and also for preventing air from being trapped in this space.

From the foregoing description it will be seen that the main control means for the sump pump unit comprises the diaphragm means 17 which are deflectable in response to changes in liquid level outside the enclosure 14 for actuating the control switch 29. With this main control means alone, as in the invention described in my earlier copending application, the pump shuts off at a predetermined minimum water level in the sump which corresponds to the level at which the buoyant or lifting effect is lost. Such operation is satisfactory in many cases, but in other situations it may be desirable to have the sump emptied to substantial dryness. The primary feature of the present invention involves an auxiliary control means which supplements and cooperates with the main control means to insure continued operation of the pump until the sump is substantially empty, as hereinafter described in detail.

Broadly speaking, the auxiliary control means which constitutes the principal feature of my invention comprises pressure-transmitting means connected to the discharge side of the pump unit for permitting the pressure of the discharge liquid from the pump to operate the main pump control. In this way the control switch is actuated independently of the liquid level outside the motor enclosure whereby the pump is kept in operation until it begins to draw air at which point the discharge pressure, of course, falls to zero.

In the embodiment of the invention shown in Fig. 1 of the drawing, the auxiliary control means comprises a conduit or pipe 36 which is threaded at one end into the pump casing on the discharge side of the pump, e. g. adjacent the pump outlet 11 as shown in the drawing. The conduit 36 terminates in an open end which is disposed below the lower diaphragm means 17 of the motor enclosure and in slightly spaced relation therefrom. Thus, it will be seen that when the pump unit 8 is in operation a stream of discharge liquid under the discharge pressure of the pump will be directed upwardly in the manner of a water jet against the lower side of the lower diaphragm means 17.

When the water level in the sump is relatively high such as to cause the float enclosure 14 to be lifted upwardly, thereby actuating the switch 29, the jet of water issuing from the conduit 36 will have no particular effect on the operation of the unit since the effect of the high water level is sufficient to keep the pump in operation. However, as the water level in the sump recedes

the tendency is for the float enclosure 14 to move downwardly, as described above, with the result that the switch 29 would eventually be shut off if there were no other force acting on the float 14. However, the force of the jet of water issuing from the conduit 36 urges the float 14 upwardly with sufficient force to insure continued operation of the pump unit 8 until the water is completely exhausted from the vicinity of the pump inlet 9. Obviously, when the pump begins to draw air through the inlet 9, there will be no liquid pressure issuing from the conduit 36 to act on the float 14 and the float will then move downwardly to shut off the motor.

Fig. 2 of the drawing illustrates a different embodiment of the auxiliary control means, the structure of the unit being otherwise the same as in Fig. 1. The same reference numerals are employed in Fig. 1 and Fig. 2 to illustrate the various parts of the motor, pump unit, and float enclosure. In this form of the invention, the auxiliary control device comprises a conduit 37 threaded at one end into the pump casing adjacent the discharge outlet as in Fig. 1. However, instead of the outer end of the conduit being open to direct a jet of water therefrom, the outer end of the conduit 37 is fitted with an expandable bellows 38. The bellows 38 is made of a resilient material such as rubber and the outer closed end thereof is positioned in flatwise contact with the lower diaphragm means 17 of the float enclosure 14. It will be understood that when the pump unit 8 is in operation and liquid is being discharged from the outlet 11, the pressure of the discharge liquid in the conduit 37 will cause the bellows 38 to expand thereby exerting a lifting or upwardly directed force on the bottom of the float 14. As described above in connection with Fig. 1, the lifting effect of the bellows 38 insures that the float 14 will be retained in its upper position for continued operation of the pump unit 8 even when the water level in the sump outside the float has diminished to the point where the buoyant effect of the water would no longer lift the float upwardly. Thus, operation of the pump continues until the sump is substantially dry and the pump begins to draw air at which point the bellows 38 will collapse and the float 14 will automatically return to its lower position thereby stopping the operation of the pump.

As a result of the combination of the main control means comprising the deflectable diaphragm and the auxiliary control means constituting the principal feature of the present invention, I am able to control the operation of the pump to insure that the sump is pumped to substantial dryness. The main control means functions primarily to reduce the water level in the sump to a certain minimum point and thereafter the float enclosure surrounding the pump motor is actuated by the auxiliary control means in response to the pressure of the discharge liquid from the pump. Consequently, it may be said that the main control means functions in response to changes in liquid level in the sump, whereas the auxiliary control means functions independently of the liquid level in the sump. Thus, the auxiliary control means constitutes an important adjunct to a submersible sump pump of the type described in the present application and in my earlier copending application. This feature is of particular importance in a situation wherein it is desirable to maintain a sump in a substantially dry condition rather than merely maintain-

ing the water level at some predetermined minimum.

Although the invention has been described in connection with certain specific structural embodiments, it will be understood that various modifications and equivalent structures may be resorted to without departing from the scope of the invention as defined in the appended claims.

10 I claim:

15 1. In a motor driven sump pump, a pump unit, an electric motor connected to said pump unit, a casing structure around said motor to render the same submersible, a control switch for said motor within said casing structure, said casing structure including diaphragm means disposed in operative relation with said switch and deflectable in response to changes in liquid level outside said casing structure for actuating said switch, and means responsive to the liquid pressure at the discharge side of said pump unit for maintaining said diaphragm means in switch-actuating position as long as liquid is being discharged from said pump unit.

20 2. In a motor driven sump pump, a pump unit, an electric motor connected to said pump unit, a casing structure around said motor to render the same submersible, a control switch for said motor within said casing structure, said casing structure including diaphragm means disposed in operative relation with said switch and deflectable in response to changes in liquid level outside said casing structure for actuating said switch, and means functioning independently of 25 said liquid level for deflecting said diaphragm means in response to the discharge pressure of said pump unit whereby to insure operation of said pump unit until the latter ceases to discharge liquid.

30 3. In a motor driven sump pump, a pump unit having an inlet and an outlet, an electric motor connected to said pump, a casing structure around said motor to render the same submersible, a control switch for said motor within said casing structure, said casing structure including diaphragm means disposed in operative relation with said switch and deflectable in response to changes in liquid level outside said casing structure for actuating said switch, and means communicating between said outlet and said casing structure for effecting deflection of said diaphragm means by the pressure of the discharge liquid from the pump whereby to insure operation of the pump until said inlet begins to draw air.

35 4. In a motor driven sump pump, a pump unit, an electric motor connected to said pump unit, a control switch for said motor, casing structure around said motor to render the same submersible, main control means for said pump unit comprising a flexible diaphragm constituting an end portion for said casing structure and deflectable in response to changes in liquid level outside said casing structure for actuating said switch, and auxiliary control means comprising a conduit 40 communicating at one end with said pump unit at the discharge side of the latter and having its opposite end disposed adjacent said casing structure for effecting deflection of said diaphragm in response to the pressure of the discharge liquid from the pump unit whereby to insure operation of the pump unit until the latter ceases to discharge liquid.

45 5. In a motor driven sump pump, a pump unit, an electric motor, a hollow float chamber sur-

rounding said motor to render the same submersible, said float chamber being supported on said motor for limited movement relative thereto, a control switch for said motor within said float chamber, said control switch being adapted to be actuated upon movement of said float chamber in response to changes in liquid level outside said float chamber, and means for moving said float chamber in response to the discharge pressure of effluent liquid from said pump unit whereby said pump unit is maintained in operation as long as liquid is being discharged therefrom.

6. In a motor driven sump pump, a pump unit, an electric motor, a hollow float chamber surrounding said motor to render the same submersible, said float chamber being supported on said motor for limited movement relative thereto, a control switch for said motor within said float chamber, said control switch being adapted to be actuated by the upper portion of said float chamber upon movement of the latter in response to changes in liquid level outside said float chamber, and conduit means connected to the discharge side of said pump unit for imposing the pressure of the discharge liquid from said pump unit against the bottom portion of said float chamber whereby to lift the latter upwardly and thereby insure continued operation of said pump unit as long as liquid is being discharged therefrom.

7. In a motor driven sump pump, a pump unit, an electric motor connected to said pump unit, a hollow float chamber surrounding said motor to render the same submersible and supported for limited movement relative to said motor, a control switch for said motor within said float chamber, said control switch being adapted to be actuated upon movement of said float chamber in response to changes in liquid level outside said float chamber, and a conduit communicating with the discharge side of said pump unit and terminating in an open end closely adjacent the bottom portion of said float chamber, said conduit thereby being arranged to direct a stream of discharge liquid against said float chamber for lifting the latter upwardly whereby to insure continued operation of the pump unit until the latter ceases to discharge liquid.

8. In a motor driven sump pump, a pump unit, an electric motor connected to said pump unit, a hollow float chamber surrounding said motor to render the same submersible and supported for limited movement relative to said motor, a control switch for said motor within said float chamber, said control switch being adapted to be actuated upon movement of said float chamber in response to changes in liquid level outside said float chamber, a conduit communicating at one end thereof with the discharge side of said pump unit and extending toward said float chamber, and an expansible bellows connected to the opposite end of said conduit and adapted to engage the bottom portion of said float chamber, said bellows thereby being adapted to be expanded by the pressure of the discharge liquid during operation of the pump whereby to lift said float chamber upwardly and thereby insure continued operation of the pump unit until the latter ceases to discharge liquid.

9. Auxiliary control means for a motor driven sump pump having a pump unit, an electric motor, a control switch for the motor, and a motor enclosure including a deflectable diaphragm adapted to actuate said control switch, said control means including a conduit communicating at one end thereof with the discharge side of the pump unit and extending toward said enclosure, and means for imposing the pressure of the discharge liquid in said conduit against said enclosure whereby to deflect said diaphragm and thereby insure continued operation of the pump unit until the latter ceases to discharge liquid.
